NOVELTY FOLDER

Warren Franke, Brooklyn, N. Y.

Application January 18, 1939, Serial No. 251,556

10 Claims. (Cl. 46—36)

This invention relates to new and useful improvements in a novelty folder.

The invention has for an object the construction of a novelty folder which is characterized by a pair of leaves of cardboard or other similar material connected together to open like a book, and a strip of material mounted thereon and operating in conjunction with a member or leaf attached on the rear face of the back leaf to cause a portion of the strip to extend above the top of the folder when the leaves are opened.

More specifically, the invention contemplates the provision of the strip of cardboard or the like material to be attached upon the outer face of the front leaf and to extend past the hinged connection of the leaves and to be formed with a fold at an acute angle to the hinge connection and to have a rear section continuing from said fold and extending to the rear of the back leaf and normally located beneath the top edge of the back leaf, and cooperative with a member attached on the rear face of the back leaf and adapted to cause said fold to straighten out when said leaves are opened to project the rear section of the strip above the top of said back leaf.

Still further the invention contemplates constructing said member in the form of an auxiliary leaf extending substantially across the entire back of the rear leaf but attached only to a portion thereof so that the rear section of the strip is free to move between these parts.

Still further the invention proposes as a modification the provision of a means for adjustably holding the strip of cardboard material previously referred to to assume various raised and lowered angular positions so that it is possible to make adjustment to project the rear section of the strip of material to various heights when the folder is opened.

As a further modified form of the invention it is proposed to form the novelty folder in a manner so that the strip portion is bent from one of the leaves of the folder and is formed in a particular manner to be cooperative with the other leaf of the folder to cause the projection and retraction of a portion of the strip.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a novelty folder constructed according to this invention and shown in the folded condition.

Fig. 2 is a perspective view of the folder in an open position.

Fig. 3 is a perspective view of the folder in a partially opened position and viewed from the rear looking down from the top.

Fig. 4 is a fragmentary perspective view similar to the upper corner of Fig. 1 but illustrating a modification of the invention.

Fig. 5 is a fragmentary vertical sectional view taken on the line 5—5 of Fig. 4.

Figs. 6 and 7 are perspective rear views of a modified form of novelty folder, showing the same in partially folded position.

Fig. 8 is a rear perspective view illustrating the folder shown in Fig. 6, in folded condition.

Fig. 9 is a perspective view of the same in open position.

The novelty folder, according to this invention, includes a pair of cardboard or the like leaves 10 and 11 connected together at one of their sides so that they may open and close like a book. Preferably, the leaves 10 and 11 are formed from one sheet of material which is folded along the line 12 to produce the pair of leaves hingedly connected. A strip of cardboard material 14 or the like material is attached upon the outer face of the front leaf 10 and extends past the hinge connection 12 of the leaves and is formed with a fold 15 at an acute angle to the hinge connection 12 and this strip 14 has a rear section 14a which continues from the front section at the fold 15 to the rear face of the back leaf 11.

This rear section 14a is normally located below the top edge of the rear section, as may be understood by the dotted lines in Fig. 1, that is, when the folder is in its folded condition. A member 16 is attached to the rear section of the back sheet 11 and is adapted to straighten out the fold 15 when the leaves 10 and 11 are opened and to keep rear section 14a in proper position relative to its use. The parts are so arranged that when this fold is straightened out the rear section 14a of the strip of material will be projected above the top of the rear leaf as illustrated in Fig. 2.

The member 16 preferably is in the form of a leaf which continues from the outer edge 11a of the rear leaf 11. This leaf 16 merely extends across the back face of the rear leaf 11. It is secured by adhesive 17 illustrated in Figs. 1 and 3 by the dotted lines, to the back face of the rear leaf. The leaf 16 is only secured at a point 55

below the normal position of the rear section 14^a of the strip of material 14. The arrangement is such that when the folder is being opened it is possible for the top portion of the rear leaf 16 to flex backwards, as illustrated in Fig. 3, and act as a spring to flatten out the fold 15, once the fold line 15 has passed the edge of the member 16.

The strip of material 14 may be imprinted with advertising material 18 or other printed material. 10 The folder itself may be imprinted for various purposes such as to comprise a menu, greeting card, or any other adaptable printed or illustrated matter. The extendable rear section 14^a is also imprinted with material 19 comprising advertising 15 material, a slogan or other similar material.

When the folder is closed from the position illustrated in Fig. 2, exactly the reverse will take place from that when the folder was opened. The fold 15 will first flex the member 16 rearwards 20 until the fold passes the edge of the member 16 and then the member 16 will assist in flattening out the rear section of the strip 14 and the parts will again assume their original position illustrated in Fig. 1 with the rear section of the strip 25 14 in its retracted position.

In Figs. 4 and 5 a modified form of the invention has been disclosed which distinguishes from the prior form in the fact that the strip of material 14 has been adjustably mounted upon the front leaf 10 in a way so that the strip may be adjusted 30 in various positions to cause the projection of the rear section 14^a to various positions. Specifically, there is a small bolt and nut 20 which engages through an aperture 21 in the strip of material 14 35 and which engages into a cross shaped aperture 22 formed in the front leaf 10.

The bolt and nut 20 may be loosened and the strip 14 shifted upwards or downwards in the vertical arm of the cross shaped opening 22, or it 40 may be shifted laterally in the horizontal arm, or it may be pivoted to various positions in either the vertical or the horizontal arms. A change of this character will change the acute angle between the fold 15 and the hinge edge 12 of the folder and 45 consequently will control the extent to which the rear section 14^a will be projected when the folder is opened. This rear section may be imprinted with messages which may be partially concealed or exposed to view according to the adjustment 50 of the strip of material 14. In other respects this form of the invention is similar to the other form.

In Figs. 6-9 inclusive a modified form of the invention has been disclosed which is characterized by a pair of cardboard or the like leaves 10 55 and 11 connected together at one of their sides by a fold 12 to open and close like a book. The upper portion of the front leaf 10 is bent down to form a strip of cardboard or the like material 14' disposed on the outer face of the front leaf 10 and extending past the hinge connection 12 of the leaves. This strip of material 14' is formed with a fold 60 15 which is disposed at an acute angle to the hinge connection 12. The strip 14' has a rear projecting section 14^a connected with the fold 15 and continuing to the rear face of the back leaf 11. This rear section 14^a is normally disposed beneath the top edge of the back leaf as shown in Figs. 6, 7 65 and 8.

The strip of material 14' is connected by a bend 70 14^b to the main portion of the front leaf 10. This bend is arranged at an obtuse angle to the hinge connection 12 (see Fig. 8). The strip 14' is permanently secured face to face upon the outer face of the leaf 10 by adhesive material 14^c.

75 Advertising or other material 18 is printed on

the exposed rear face of the strip 14'. Advertising or other material 19 is printed on the front face of the rear section 14^a of the strip. This latter material is normally hid from view except when the leaves 10 and 11 are moved to their open position. An auxiliary leaf 16' is connected by a fold 11^a with the outer edge of the leaf 11.

5 The operation of the device is as follows:

Fig. 8 shows the folder closed. When the leaves 10 and 11 are opened it will be found that the rear section 14^a of the strip is in the path of motion of the rear leaf 11 which forces the same backwards and in so doing opens the fold 15. This straightens out the strip 14 and then the portion 14^a will be projected above the top edge of the 15 leaf 11. When the folder is closed the fold 15 will partially close due to the resiliency of the material so that the rear section 14^a will move partially 20 downwards beneath the top edge of the leaf 11. When the auxiliary leaf 16' is closed down upon the leaf 11 the fold 15 will be completely closed and the article will again be in the position shown in Fig. 8.

While I have illustrated and described the preferred embodiments of my invention, it is to be 25 understood that I do not limit myself to the precise constructions herein disclosed and the right is reserved to all changes and modifications coming within the scope of the invention as defined in the appended claims.

Having thus described by invention, what I 30 claim as new, and desire to secure by United States Letters Patent is:

1. A novelty folder, comprising a pair of cardboard or the like leaves connected at one side to 35 open like a book, a strip of cardboard or the like material carried by the outer face of the front leaf and extending past the hinge connection of the leaves and formed with a fold at an acute angle to the hinge connection and having a rear 40 section connecting from said fold and continuing to the rear face of the back leaf and normally located beneath the top edge of said back leaf, and a member attached to the rear face of the back leaf and adapted to straighten said fold when 45 said leaves are opened to project the rear section of said strip above the top of said back leaf.

2. A novelty folder, comprising a pair of cardboard or the like leaves connected at one side to 50 open like a book, a strip of cardboard or the like material carried by the outer face of the front leaf and extending past the hinge connection of the leaves and formed with a fold at an acute angle to the hinge connection and having a rear 55 section connecting from said fold and continuing to the rear face of the back leaf and normally located beneath the top edge of said back leaf, and a member attached to the rear face of the back leaf and adapted to straighten said fold when 60 said leaves are opened to project the rear section of said strip above the top of said back leaf, said member comprising an auxiliary leaf of material attached at a portion thereof to the back face of the rear leaf.

3. A novelty folder, comprising a pair of card- 65 board or the like leaves connected at one side to open like a book, a strip of cardboard or the like material carried by the outer face of the front leaf and extending past the hinge connection of the leaves and formed with a fold at an acute angle to the hinge connection and having a rear 70 section connecting from said fold and continuing to the rear face of the back leaf and normally located beneath the top edge of said back leaf, and a member attached to the rear 75

face of the back leaf and adapted to straighten said fold when said leaves are opened to project the rear section of said strip above the top of said back leaf, said member comprising an auxiliary leaf of material attached at a portion thereof to the back face of the rear leaf, said auxiliary leaf comprising a continuation of said rear leaf.

4. A novelty folder, comprising a pair of cardboard or the like leaves connected at one side to open like a book, a strip of cardboard or the like material carried by the outer face of the front leaf and extending past the hinge connection of the leaves and formed with a fold at an acute angle to the hinge connection and having a rear section connecting from said fold and continuing to the rear face of the back leaf and normally located beneath the top edge of said back leaf, and a member attached to the rear face of the back leaf and adapted to straighten said fold when said leaves are opened to project the rear section of said strip above the top of said back leaf, said member comprising an auxiliary leaf of material attached at a portion thereof to the back face of the rear leaf, said auxiliary leaf comprising a continuation of said rear leaf, and said auxiliary leaf being secured to the rear face of the back leaf at an area below the position of the rear section of said strip of material.

5. A novelty folder, comprising a pair of cardboard or the like leaves connected at one side to open like a book, a strip of cardboard or the like material carried by the outer face of the front leaf and extending past the hinge connection of the leaves and formed with a fold at an acute angle to the hinge connection and having a rear section connecting from said fold and continuing to the rear face of the back leaf and normally located beneath the top edge of said back leaf, and a member attached to the rear face of the back leaf and adapted to straighten said fold when said leaves are opened to project the rear section of said strip above the top of said back leaf, said rear section of said strip of material being of an ornamental design and shape.

6. A novelty folder, comprising a pair of cardboard or the like leaves connected at one side to open like a book, a strip of cardboard or the like material carried by the outer face of the front leaf and extending past the hinge connection of the leaves and formed with a fold at an acute angle to the hinge connection and having a rear section connecting from said fold and continuing to the rear face of the back leaf and normally located beneath the top edge of said back leaf, a member attached to the rear face of the back leaf and adapted to straighten said fold when said leaves are opened to project the rear section of said strip above the top of said back leaf, and means for adjustably attaching said strip upon the front leaf to assume various raised and lowered and angular positions.

7. A novelty folder, comprising a pair of cardboard or the like leaves connected at one side to open like a book, a strip of cardboard or the like material carried by the outer face of the front leaf and extending past the hinge connection of the leaves and formed with a fold at an acute angle to the hinge connection and having

a rear section connecting from said fold and continuing to the rear face of the back leaf and normally located beneath the top edge of said back leaf, a member attached to the rear face of the back leaf and adapted to straighten said fold when said leaves are opened to project the rear section of said strip above the top of said back leaf, and means for adjustably attaching said strip to the front leaf to assume various raised and lowered and angular positions, comprising a bolt and nut mounted through said strip of material and through elongated openings formed in the front leaf.

8. A novelty folder, comprising a pair of cardboard or the like leaves connected at one side to open like a book, a strip of cardboard or the like material carried by the outer face of the front leaf and extending past the hinge connection of the leaves and formed with a fold at an acute angle to the hinge connection and having a rear section connecting from said fold and continuing to the rear face of the back leaf and normally located beneath the top edge of said back leaf, a member attached to the rear face of the back leaf and adapted to straighten said fold when said leaves are opened to project the rear section of said strip above the top of said back leaf, and means for adjustably attaching said strip to the front leaf to assume various raised and lowered and angular positions, comprising a bolt and nut mounted through said strip of material and through elongated openings formed in the front leaf, said elongated openings being in the form of a cross, said bolt being engageable along the arms thereof and the strip of material being turnable to various positions along the bolt.

9. A novelty folder, comprising a pair of cardboard or the like leaves connected at one of their sides to open like a book, a strip of cardboard or the like material on the outer face of the front leaf and extending past the hinge connection of the leaves and formed with a fold at an acute angle to the hinge connection and having a rear section connecting with said fold and continuing to the rear face of the back leaf and normally located beneath the top edge of said back leaf, and said rear section being in the path of motion of said back leaf when said leaves are opened to straighten said fold and project the rear section of said strip above the top of said back leaf.

10. A novelty folder, comprising a pair of cardboard or the like leaves connected at one of their sides to open like a book, a strip of cardboard or the like material on the outer face of the front leaf and extending past the hinge connection of the leaves and formed with a fold at an acute angle to the hinge connection and having a rear section connecting with said fold and continuing to the rear face of the back leaf and normally located beneath the top edge of said back leaf, and said rear section being in the path of motion of said back leaf when said leaves are opened to straighten said fold and project the rear section of said strip above the top of said back leaf, and the front portion of said strip of material being permanently pasted down upon the rear face of said front leaf.
